United States Patent Office.

HUGH LAIRD, OF MECHANICSBURG, PENNSYLVANIA.

Letters Patent No. 78,294, dated May 26, 1868.

IMPROVEMENT IN HORSE HAY-FORKS.

The Schedule referred to in these Letters Patent and making part of the same.

TO ALL WHOM IT MAY CONCERN:

Be it known that I, HUGH LAIRD, of Mechanicsburg, in the county of Cumberland, and State of Pennsylvania, have invented new and useful Improvements in Hay-Elevating Forks; and I do hereby declare the following to be a full and clear description of the same, sufficient to enable others skilled in the art to which my invention appertains to fully understand and use the same, reference being had to the accompanying drawings which make part of this specification, and in which—

Figures 1 and 2 are side elevations of my improved hay-elevating fork, showing the parts in different position.

Figure 3 is a longitudinal section of the same, and

Figure 4 is an edge view.

Similar letters of reference indicate corresponding parts in the several figures.

The subject of this invention is a hay-elevating fork of the harpoon kind, and the invention consists in making the stock or main part out of a single piece, or casting it entire; in the provision of an arm projecting horizontally from the upper end of the fork, and serving to carry an additional guide or loop for the tripping or discharging-rope, so as to prevent the rotation of the fork while being elevated; and finally, in the employment of a rigid bow or compressing-bar, attached to the slide which operates the tines or lifting-prongs, and serving to confine a larger quantity of hay upon said tines than the latter could take up alone.

In the drawings, A may represent the stock or main part of the instrument, which is cast entire, or otherwise formed so as to consist of but one part. Within the stock A is a longitudinal opening containing the slide B, pivoted to the lower end of which are the tines or elevating-prongs C C. The prongs C are protruded, as shown clearly in figs. 1 and 3, when the slide B is depressed, the curved shape of the prongs, together with the internal formation of the stock at its lower end, causing said prongs to freely glide out through the openings a a.

In the sides of the stock are longitudinal slots a', which allow the free vertical movement of a bow or curved bar D, which is rigidly attached to the slide B, and which projects an equal distance at each side of the stock.

The operation of the above-described parts will be readily understood. The slide B being elevated so as to draw the prongs C C within the stock A, and raise the bar D, as shown in fig. 2, the fork is thereby placed in readiness to penetrate the hay. The fork having been inserted into the hay, the slide B is depressed, in consequence of which the prongs C C are forced out of the stock, so as to occupy a position at right angles to the stock A, or nearly so, and the bar D is simultaneously brought down and made to compress the hay above or upon the prongs C C. These relative positions of the parts are maintained by the engagement of the trigger E with the shouldered recess b in the slide B, so that the hay raised upon the prongs C C is securely retained thereupon by the curved compressing-bar D. The elevating-rope is attached to the upper end of the slide B, and the trigger E is pivoted to the stock A, so that, when the fork is raised to the point where the hay is to be deposited, the disengagement of the trigger E from the shoulder of b allows the stock A to move downward under the weight of its load, and thus the prongs C C are drawn within the stock while the pressure of bar D is removed. The hay thus losing its support, is discharged. The trigger E is pulled by means of the rope or cord F.

It is manifest that by the above-described device D, the lifting or retaining-capacity of the fork is greatly increased.

Projecting rigidly from the upper end of the stock A is an arm, G. The tripping-rope F passes through an eye, loop, or other guide, at the outer end of the arm G, thence through a loop on the top of slide B, and thence to the trigger E, to which said rope is attached. The employment of the arm G in connection with the tripping-rope subserves a very useful purpose, for it enables a person having hold of the tripping-rope to prevent the rotation of the fork, and the consequent twisting of the elevating-rope while the hay is being elevated.

The bar D is preferably curved as shown, but may be straight if convenience or circumstances should render such form desirable.

Having thus described my invention, what I claim as new, and desire to secure by Letters Patent, is—
The combination of the compressing and retaining-bar or bow D, with the elevating-tines or prongs C C,
operating substantially as and for the purpose described.

To the above specification of my improvement in hay-forks, I have signed my name, this day, the eleventh
of February, 1868.

HUGH LAIRD.
